UNITED STATES PATENT OFFICE.

HENRY Z. COBB, OF WINCHESTER, MASSACHUSETTS, ASSIGNOR TO REVERE RUBBER COMPANY, OF CHELSEA, MASSACHUSETTS, AND PROVIDENCE, RHODE ISLAND, A CORPORATION OF RHODE ISLAND.

BILLIARD-CUSHION.

1,138,933.

Specification of Letters Patent. Patented May 11, 1915.

Application filed June 6, 1913. Serial No. 772,020.

To all whom it may concern:

Be it known that I, HENRY Z. COBB, a citizen of the United States, residing at Winchester, county of Middlesex, State of Massachusetts, have invented certain new and useful Improvements in Billiard-Cushions, of which the following is a full, clear, and exact disclosure.

My invention relates to that class of billiard cushion made in the usual triangular form and composed of rubber composition, vulcanized in the usual manner, and includes means for improving the elastic quality of the cushion and the accuracy and amount of rebound of a billiard ball when striking the cushion. Heretofore in the art it has been customary in some forms of cushions to embed in the billiard cushion near the nose thereof, metallic wire or other similar material, which has also been in the form of strands or plates. However, in some forms of these cushions difficulty has been experienced in obtaining a firm adhesion between the metal when used, and the rubber itself. Difficulty has also been experienced in arranging the cloth or canvas embedded in or applied to the cushion, so that efficient coöperative action is attained.

The object of my invention, therefore, is to so embed metallic wire in the cushion that the adhesion between the rubber and the metal is greatly increased, and also to so arrange the fabric that the same co-operates with the wire and prevents the nose of the cushion from being forced upward independent of its horizontal movement or yielding quality in opposition to the horizontal movement of the billiard or pool ball.

For a detailed description of one form of my invention, reference may be had to the following specification and to the accompanying drawing forming a part thereof, in which:

Figure 1 is a perspective view of the triangular rubber strip of a billiard cushion, part of the same being cut away to show the internal construction; Fig. 2 is a perspective view of the reinforcing wire; and Fig. 3 is a transverse sectional view of the cushion.

Referring to the drawing, the numeral 1 indicates a metal wire, preferably steel piano wire, which is covered by a layer of

fine braided steel wire or metallic thread 2 55 which is tightly braided about the steel core, in the manner well known in the manufacture of braided coverings for wire, such as insulation, etc. The braided wire cover produces a roughened outer surface, into the 60 interstices of which the rubber composition may easily penetrate. This produces an adhesion impossible to accomplish in any other manner. The braiding of the fine wire about the central steel core produces a uniform tension in the covering and also an even distribution of the covering which is not possible when wound with a layer of cloth. After the wire covering is braided about the central core, the same may be 65 treated with a solution to insure a more perfect chemical adhesion or contact between the rubber and the metal. The cushion is then made up in the usual manner, so that the braided wire is located near the nose of 70 the cushion at a distance $\frac{1}{8}$ to $\frac{1}{2}$ of an inch back from the line of contact with the billiard ball. The steel wire core with its covering is first placed on the corner or edge 75 of the core 3 and the rubber strip 4 is then 80 placed around the two adjacent sides of the core, including the reinforcing wire and its covering. A strip 5 of cloth or duck is then placed about the surfaces of the cushion to be covered thereby and the cushion so assembled is placed in a suitable mold to be cured or vulcanized in the ordinary way. The cloth or duck 5 is preferably so located as to extend toward or around the nose of the cushion, as shown in Figs. 1 and 85 90 3. By this means the cushion is held down against the tendency to move upward when struck by a billiard ball. The margin of the canvas strip 5 being near the wire 1, there is not such a rigid connection between the two 95 that the resiliency is reduced; while on the other hand, the apex of the cushion is held in position without contacting with the wire and its covering. The duck or fabric may be applied to the surface of the cushion in 100 other ways, but that illustrated in the figures of the drawing is deemed preferable.

I appreciate that it is old in the art to wind a steel wire with cloth or textile fabric for the purpose of increasing the connection 105 between the rubber and wire, and also that it is old to wind fine wire about a steel strip in the form of a flat spring, but these con-

structions involve certain disadvantages which not only increase the cost of manufacture, but result in a less efficient and accurate cushion. I believe that it is new to 5 braid fine wire around steel piano wire as a form of stiffening or hardening device, and the construction described combines all the advantageous features of the older constructions and at the same time greatly increases 10 the amount of rebound of a billiard ball, or what is known by billiard players as "legs", and the reflection of the ball on the billiard cushion is rendered more accurate. In other words, the angle of reflection is substantially 15 equal in all cases to the angle of incidence.

Having thus described this form of my improved cushion, what I claim and desire to protect by Letters Patent is:

1. A billiard cushion comprising a main 20 body of vulcanized rubber having hard, resilient metallic wire embedded near the contact edge thereof, said wire being covered with a tightly braided layer of metallic filamentary material.
2. A billiard cushion comprising a main 25 body of vulcanized rubber having steel

piano wire embedded near the contact edge thereof, said wire being covered with a tightly braided layer of metallic filamentary material.

3. A billiard cushion comprising a main body of vulcanized rubber having steel piano wire embedded near the contact edge thereof, said wire being covered with a tightly braided layer of steel filaments.

4. A billiard cushion comprising a main body of vulcanized rubber having hard resilient metallic wire embedded near the contact edge thereof, said wire being covered with a tightly braided layer of metallic filaments, and a covering of fabric vulcanized to the lower face of the cushion strip and extending toward its contact edge to a point adjacent said wire.

Signed at Chelsea, county of Suffolk, 45 State of Massachusetts, this 26 day of May, 1913.

HENRY Z. COBB.
